UNITED STATES PATENT OFFICE

2,631,588

BOOTH FOR GIVING TAN TREATMENTS

Anthon H. Paschell, Des Moines, Iowa

Substituted for abandoned application Serial No. 658,652, April 1, 1946. This application July 17, 1950, Serial No. 174,311

8 Claims. (CL. 128—371)

1

This invention relates to an improved booth or cabinet adapted to be situated in a beauty parlor or public gathering place, such as a drug store or a rest room, to provide a temporary and easy accessible place of privacy for any person desiring to renew a badly worn makeup or to fix or adjust a torn or dislocated garment, and is a substitute for application for a Booth for Giving Tan Treatments, filed April 1, 1946, Serial Number 658,862, which became abandoned on October 13, 1949.

This invention further and more particularly relates to a booth of the type above described and including a bank of coin controlled ultra violet lamps so constructed and arranged that a person positioned within the booth may, by placing a coin in a suitable coin controlled mechanism, automatically receive radiant energy from the lamps for a predetermined length of time for treatment similar to that produced by sunlight without burning and without the usual expense and trouble experienced in obtaining a sun treatment.

In the northern and colder climates when people have to wear heavy clothing in the winter months to keep warm, it is the custom for them in the summer and hot months to clothe very lightly to keep cool, often having a large portion of the body uncovered and exposed to the sun, in which case the bleached or white skin is not very becoming and is easily blistered. To overcome this difficulty it is customary to tan the skin by short exposure to direct sunlight at such times and places as are provided, often resulting in blisters and sunburns. To many people the time and proper place for such exposure is not available.

In the last few years it has become the fad for teen age girls and some ladies to wear short stockings and often none at all in which case the white skin is not very becoming. Therefore they either paint their legs a tan color or produce a tan by exposure to the sun to give the desired color. The painting is very undesirable in that it has to be applied every day and often is streaked, and the tanning by the sun method is often impossible and sometimes inconvenient.

The object of my invention is to provide a booth or cabinet of the type above described, located at any convenient place whereby any person desiring a tan can secure treatment to produce a partial tan by entering the booth and placing a coin in a suitable receptacle, provided for that purpose, including a time controlled mechanism with automatically controlled means for energiz-

2

ing the interior of the cabinet with ultra violet light for a predetermined length of time, whereby the total or complete treatment is produced by a number of consecutive treatments rather than by single exposure to the sun as is sometimes customary which results with the undesirable burning or blistering.

A further object of my invention is to provide a booth so constructed and arranged that a person having bare legs and desiring a leg tan can do so by entering the booth, closing the door, adjusting a combined shield and skirt support to proper position and then inserting a coin in a coin controlled device, obtain a treatment for a predetermined length of time without removing any of the clothing.

A further object is to provide in a booth for giving tan treatments an auxiliary compartment so constructed and equipped that a person desiring a tan treatment of portions of the body covered by clothing can do so by removing clothing from that portion of the body to be treated and placing them in said compartment in position out of the influence of the ultra violet energy.

Another object of my invention is to provide a booth for giving tan treatments, employing a plurality of vertically and annularly arranged tubular lamps for producing ultra violet energy of a height equal to or greater than the height of that portion of the body being treated, whereby a more uniform treatment may be had.

A further object of my invention is to provide in a booth for giving tan treatments a lower bank of vertically and annularly arranged tubular lamps for producing ultra violet energy for giving leg tan and a second and similar bank of lamps supported above the first bank of lamps for treatment of the upper portion of the body, and means for energizing either one or both of said banks of lamps either independently or simultaneously.

A further object is to provide in a booth for giving tan treatment, and that type employing electric means, including an electric circuit, for producing ultra violet energy and a switch for opening and closing said circuit, a coin controlled device for causing said switch to move to a closed position and a time controlled device for causing said switch to be moved to open position.

More specifically it is the object of my invention to provide in a booth for giving treatments for leg tan, including a plurality of upright tubular lamps for producing ultra violet energy, supported adjacent to the interior surface of the

booth, improved means for shielding the eyes of the person taking treatments and for supporting the skirts while the treatment is being given.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a perspective view of my improved booth with the door in an open position.

Figure 2 is a vertical sectional view of the same with the door closed, and in dotted lines a person in proper position for taking a leg tan treatment.

Figure 3 is a sectional view taken on the line 3—3 of Figure 2.

Figure 4 is a sectional view taken on the line 4—4 of Figure 3.

Figure 5 is a detailed sectional view taken on the line 5—5 of Figure 1.

Figure 6 is an enlarged detailed sectional view taken on the line 6—6 of Figure 5.

Figure 7 illustrates diagrammatically the electric circuits for energizing ultra violet lamps and the mechanism for controlling said circuits.

Figure 8 illustrates diagrammatically the means for causing both circuits to be operated in unison when a coin is placed in a control device for actuating the upper circuit.

Figure 9 is a detail view of the device for causing the sets of circuit contacts to be operated in unison.

Figure 10 is an enlarged detail view of a portion of the door and the front view of the lock also showing the coin slot.

Referring to the accompanying drawings I have used a reference numeral 10 to indicate the housing of my improved booth. Said housing comprises a back 11, a front 12, sides 13, a top 14 and a bottom 15.

The front 12 is provided with a door opening 16. Supported within the opening 16 by means of suitable hinges 17 is a door 18. The front, back and sides are provided with a louvers 19 for ventilating purposes. The back 11 is provided with a cabinet 20 communicating with the interior of the housing 10 by means of an opening 21 to provide a clothes closet for the purpose hereinafter more fully set forth.

A door 22 is slidably mounted in guides 23 for closing said door opening. The back wall of the closet is provided with a forwardly and laterally projecting rod 24 for supporting a clothes hanger 25. The door 18 is provided with a lock 26, designed to automatically lock the door to a closed position. The lock is provided with a coin controlled device 27 to cause the latch of the lock to be released upon the insertion of a coin through the slot 28. By this arrangement the door 18 is locked against any person entering the cabinet except at such times as when a coin is inserted in the said slot 28.

A person may enter the cabinet by grasping a knob 29 forming a part of said lock and rotating it in the usual manner. The latch may be released by a person within the cabinet by means of the knob 30. Mounted in each corner of the housing 10 is a pair of upright tubular lamps 31 and 32 of the type for radiating ultra violet energy. The lamps 31 are substantially of a height 24 inches while the lamps 32 are substantially 28 inches in height. The lamps 32 are preferably mounted about the lamps 31 in a manner clearly illustrated in Figures 1, 2 and 3. The lamps are

detachably mounted in brackets 33 supported by insulation blocks 34 mounted on the side members 13 of the housing.

I will now describe the electric circuits for energizing the lamps 31 and 32, it being understood that the circuits herewith shown are purely diagrammatical, as the circuits' construction forms no part of my present invention.

The power circuit 36 is coupled to the coin controlled circuit 37 by means of a step down transformer 38 to deliver a low voltage current of electricity to the relay 39. The circuit 37 includes a pair of yieldable contacts 40 supported in the coin guide 41 in such a manner that when a coin 42 is inserted in the guide 41 it will close the circuit by momentarily short circuiting the contacts. A relay circuit 43 is also provided comprising conductors 44 and 45, the conductor 44 including contacts 46 supported normally in an opened position. An armature 47 designed to be operated by the relay 39 is provided for closing said contacts 46. The conductor 45 includes the primary of a transformer 48, the secondary of said transformer including the lower lamp circuit 49. The lamps 31 are connected in parallel, as clearly illustrated, each in series with the ballast 50 and shunted with a starter 51 of ordinary construction. A conductor 52 shunts the conductor 45 and has connected therein a synchronized motor 53 adapted to operate a time controlled switch 54, adapted to control a spring actuated latch 55 mounted on a shaft 70, adapted to have its upper end engage the under surface of the armature 47 at the time the relay 39 is actuated, to lock the circuit 43 closed. Said time switch 54, comprising a worm gear 56, a ratchet 56, a pivoted arm 57, a pawl 58 pivotally supported on said arm provided with a spring 59 for yieldingly holding the pawl in either of two predetermined positions, a time adjusting lever 60 and a spring 61 for actuating the lever 57 in a clockwise direction as view in Figure 7.

A second coin controlled circuit 62 in parallel with the circuit 37 is provided for energizing the upper bank of lamps 32, comprising conductors 63 and 64, having contacts 65 and a relay 66. The contacts 65 are mounted in a coin guide 67. A second relay circuit 68 is provided including the primary of a transformer 69 and contacts 70 controlled by an armature 71 of the relay 66. A circuit 72 including the secondary of the transformer 69 is provided for energizing said lamp 32, similar to the lamp circuit 49. A latch bar 73 is yieldably mounted on a rod 74 for locking the contacts 70 in closed position at such time as when the relay 66 is energized, at which time the contacts 46 are also closed by means of a link 75. Said link is so constructed that both sets of contacts 46 and 70 will be closed simultaneously as the relay 66 is energized but only the contact 46, as the relay 39 is energized. This is accomplished by fixing the one end of the rod 75 to the armature 71 with its lower end supported under the armature 47 so that said armature 47 may be elevated without elevating the armature 71. See Fig. 8.

Pivotal secured to each side wall 13, the back 11, and to the inner face of the door 18 is what I shall term a light shield and skirt guard 76. Each guard is mounted on a shaft 77 in a suitable bearing 78a. Each end of each of the shafts 78 and 79 is provided with a miter gear 81, the adjoining ends of said shaft being thus geared together. The inner end of the shaft 77 is provided with a gear 82 adapted to move into and out of

mesh with the adjoining gear 81 as the door 18 is closed and opened. The back end of the shaft 80 is provided with a gear 83 for connecting the shafts 79 and 80. The said shaft and gears provide means whereby all of the member 76 may be lowered from the upright inoperative position illustrated in Fig. 1 to a horizontal operative position shown in Figs. 2 and 3, simultaneously by manually operating either of the guards 76. The shaft 77 and the shaft 78 are each provided with a device 84 (see Fig. 6) to frictionally retain the guards in one of a number of predetermined positions of adjustment. Said device includes a disc 85 fixed to its respective shaft, and has a series of notches 86 in its upper edge adapted to be engaged by a spring 87 secured to one of the adjacent housing walls.

The members 76 are tapered to permit them to fit substantially together when in a horizontal position as shown in Figure 4. The inner end of each member 76 is formed concaved to provide an opening 88 to be occupied by the person taking treatment. The guards when in their horizontal position serve as means for locating the person at a position at equal distances from the lamps, for shielding the eyes from energy radiating from the lower set of lamps 31 and also as means for supporting the skirts to permit the rays of energy to radiate to that portion of the skin being treated without interference, as illustrated in dotted lines in Figure 2. The operation of my improved booth is substantially as follows. Assuming that one of my improved booths has been installed in any convenient location and that the door 18 has been closed and automatically locked by the coin controlled lock 26, a person desiring to obtain a temporary place of privacy may do so by simply placing a coin such as a penny or nickel in the slot 28 within the door 18. Said coin will then cause the door latch to be released so that the door may be opened by grasping and turning the knob 29 after which the person may enter and adjust or mend any dislocated or torn garment.

Assuming that the person desires a leg tan, she enters the booth in the manner above described, takes a central position, then grasps one of the guards 76 and swings it to its lowered position after which the skirts are then drawn upwardly to position on top of said guard as shown in dotted line Fig. 2. She then inserts a coin in the guide 41 which will then slide into position between the contacts 40 and close the conductors 37. A current of electricity will then flow through the relay 39 causing the armature 47 to be elevated and conductors 44 and 45 closed, causing a current to flow through the transformer 48, and in turn the lamp circuit 49. As the armature 47 is elevated the latch 55 will be moved to position under said armature by the spring 55a, causing the contacts 46 to be locked in a closed position. Closing of said contacts will, in addition to energizing the transformer 48, cause current to flow through the conductor 52 and the motor 53. The ratchet wheel 56 will in turn be rotated by the worm 90 and the gear 91 in an anti-clockwise direction, and in turn the arm 57 by means of the pawl 58. This movement will continue until lug 92, engages the lower end of the lever 55a causing its upper end to disengage the armature 47 permitting the contacts 46 to be separated and the conductors 45 and 52 de-energized, causing the lamps 31 to be extinguished and the motor 53 stopped. The motor, due to the momentum of its moving parts, will continue

to move the cam 92 of the pawl 58 into engagement with a pin 93 causing the pawl to disengage the ratchet and to be held in said position by the spring 59, permitting the arm 57 to swing in a clockwise direction by means of the spring 61 until the cam surface 94 of said pawl engages a pin 95 carried by the arm 60, causing the pawl to again engage the ratchet 56. The length of time required for the arm 57 to travel from its normal position of rest to the position where the lug 92 engages the lever 55, represents the time that the lamp 31 will be energized. This time period may be varied by adjusting the position of the lever 60.

15. The time usually required for a treatment is about 3 minutes, time being determined by the intensity of the lamp and the distance from the person being treated. After the proper time has been determined, the position of the lever 60 is 20 pre-set so that the person taking treatment cannot change it, thereby insuring the person against burns by overexposure. The time of exposure is determined for the most delicate and transparent skins. The treatment may be repeated as 25 often as is found to be necessary to obtain the desired color.

After the treatment has been completed the person may leave the booth by first elevating the guards 76 to their upright position. Then by 30 grasping the knob 39 the latch may be released and the door opened, which will be automatically closed by the spring hinge 17 after which the booth is again ready for the next customer.

Assuming that a person desires a tan treatment for the arms and back as well as the legs, 35 has approached the booth, in which case she enters the booth in a manner above described, then removes any clothing covering that portion of the arms and back to be treated and hangs them in the closet 20, together with any other 40 outer or colored clothing that might be bleached or otherwise damaged by the ultra violet light. The door 22 is then closed after which the guards 76 may again be lowered to operative position. A 45 coin may then be placed in the guide 67 to cause both banks of lamps 31 and 32 to be energized. The contacts 65 will then be closed by the coin and the conductors 63 and 64 energized. Current from the transformer 38 will cause the relay 66 to be actuated to lift the armature 71, and the contacts 70 closed. The rod 75 serves to also lift the armature 47, and to simultaneously close the contacts 46. The latches 55 and 73 will also move to lock their respective armatures closed, after 50 which the transformers 48 and 69 are energized and in turn their respective lamp circuits 49 and 72. The motor 52 will again be started and the time controlled device 54 actuated to open both 55 circuits, and in turn both sets of lamps 31 and 32 extinguished.

60. By the above arrangement the entire exposed portions of the skin are treated simultaneously and with the same amount of exposure, inasmuch as the lamps are of a height equal to that of the exposed portion of the skin and at equal distances from said portions being treated. The device is so constructed and arranged that a person may take a treatment at his or her convenience and without the necessity of an assistant.

70. It will therefore be seen that I have provided a booth of simple, durable and inexpensive construction adapted to be placed in any convenient location, and upon the insertion of a coin of small value a person can easily and quickly find a place 75 of privacy, for renewing a worn makeup, fixing a

torn garment or for obtaining a tan treatment.

I claim:

1. In a device of the class described, the combination of a housing, a plurality of upright elongated lamps within said housing for radiating tan producing electric energy spaced apart and arranged in annular formation, and an eye shield and skirt support pivotally supported between the lamps of each set of adjacent lamps to swing from a normal upright position to an inwardly extending and substantially horizontal position, said shield being constructed to provide a space between their inner ends, to be occupied by the person being treated when the shields are in their horizontal position.

2. In a device of the class described, the combination of a housing, a plurality of upright elongated lamps within said housing for radiating tan producing electric energy spaced apart and arranged in annular formation, an eye shield and skirt support pivotally supported between the lamps of each set of adjacent lamps to swing from a normal upright position to an inwardly extending and substantially horizontal position, said eye shields being constructed to provide a space between their inner ends to be occupied by the person being treated, when the shields are in their horizontal position, and adjustable means for retaining the inclination of said shields to anyone of a number of predetermined operative positions.

3. In a device of the class described, the combination of a housing, a plurality of upright elongated lamps within said housing for radiating tan producing electric energy, spaced apart, and arranged in annular formation, an eye shield and skirt support pivotally supported between the lamps of each set of adjacent lamps to swing from a normal upright position to an inwardly extending and substantially horizontal position, gear devices for connecting said shields to operate simultaneously; said shields being constructed to provide a space between their inner ends, to be occupied by the person being treated when the shields are in their horizontal position.

4. In a device of the class described, the combination of a rectangular housing including a door in one side, an upright lamp in each corner of said housing for radiating ultra violet energy, skirt supports pivotally mounted between the lamps to swing from a normal upright position to a horizontal position, cooperative gear devices for operatively connecting said skirt supports to operate in unison, means included in said gear devices for adjustably retaining said supports to any one of a number of inclined positions, and means for conducting electric energy to said lamps.

5. In a device of the class described, the com-

bination of a rectangular housing including a door in one side, a skirt support element having one edge pivotally mounted to each of said sides and to said door to swing from a normal upright position to a horizontal position, and means carried by said housing for adjustably retaining said skirt supports to said horizontal position and to any one of a number of inclined positions.

6. In a device of the class described, the combination of a rectangular housing including a hinged door in one side, an upright lamp in each corner of said housing for radiating ultra violet energy, skirt supporting elements pivotally mounted to each of said walls and said doors, between said lamps to swing from a normal upright position to an inwardly extending position, cooperating gear devices for operatively connecting said skirt support to operate simultaneously with the door closed, means included in said gear devices for retaining all of said supports to any one of a number of inclined positions, and means for conducting electric energy to said lamps.

7. In a device of the class described, the combination of a housing of such height as to receive an occupant while standing, a combined skirt support and centralizing devices projecting inwardly from the walls of said housing intermediate their ends, a plurality of lamps above said skirt supporting elements, a second plurality of lamps below said skirt support elements, means for energizing said lower lamps independently of the upper lamps to produce a leg tan, and means for conducting electricity to all of said lamps simultaneously for producing a tan of the entire body, and time controlled means for deenergizing all of said lamps simultaneously.

8. In a device of the class described, the combination of a housing of such height as to receive an occupant while standing, a combined skirt support and centralizing device projecting inwardly from the walls of said housing intermediate their ends, a plurality of upright tubular ultra violet lamps above said skirt support, a second plurality of upright tubular ultra violet lamps below said skirt support, the lamps of the lower plurality of lamps being in vertical alignment with corresponding ones of the upper plurality of lamps to form substantially a continuous column of radiated energy equally spaced apart and of equal distances from a person being treated, means for energizing said lower lamps independently of the upper lamps to produce a leg tan, means for energizing all of said lamps simultaneously for producing a tan of the entire body, and time controlled means for deenergizing all of said lamps simultaneously.

ANTHON H. PASCHELL.
